TOOL FOR EXTRACTING AND REPLACING BUSHINGS

Filed Jan. 7, 1928

UNITED STATES PATENT OFFICE

JOHN D. HAMAN, OF WILMINGTON, DELAWARE

TOOL FOR EXTRACTING AND REPLACING BUSHINGS

Application filed January 7, 1928. Serial No. 245,172.

My invention relates to improvements for extracting and inserting bearings from and into machine parts, and my preferred embodiment is shown in connection with wrist pin bearings of pistons, wherein, as the connecting rod shaft becomes loose, the old bearings may be extracted and new ones inserted.

The principal object of my invention is to produce a tool for this purpose, which will adequately guide the bushing in both the extracting and inserting operation, thereby preventing clogging of the bushing as well as a deformation thereof.

Another object of my invention is to produce a tool which is simple in construction and operation, is inexpensive to manufacture, yet sturdy and efficient as well as being composed of a minimum of parts.

Another object of my invention is to adapt the tool parts so that the same may be held in alignment during use, facilitating a ready operation thereof.

Other objects of my invention will be apparent from the detailed description of my preferred embodiment as illustrated in the accompanying drawings in which:

Figure 1 is a sectional view of a piston showing my tool applied to extract an old bushing.

Fig. 2 is a sectional view of a piston showing my tool applied to insert a new bushing.

Fig. 3 is a side view of my improved wrench used in connection with my tool, and

Fig. 4 is a side view of the several elements of the tool spaced apart for illustrative purposes.

Proceeding with a detailed description of the tool constructed in accordance with my invention I employ a screw-threaded shaft as the principal power element, said shaft being operated or turned by a hand lever in the form of a cross-bar 2 and is adapted to be used with cooperating parts or accessories employed in the operation of inserting and withdrawing bushings, as hereinafter set forth: This shaft includes an unthreaded or plain portion 3 and a threaded portion 4, and the external diameter thereof, throughout its length, is of the same diameter as the internal diameter of the bushings to be operated on

by the tool; the handle or cross-bar extending through a hole therefor near the outer end of the unthreaded portion of said shaft with a washer 5 interposed between the same and a part of the tool hereinafter referred to, said washer constituting a thrust portion of the shaft which is adapted to receive the thrust of the tool.

For the extracting operation, illustrated in Fig. 1, I employ in connection with the aforementioned shaft a loose compression sleeve 6, extracting nut 7 and wrench 8. The sleeve comprises a cylindrical body portion 9 provided at one end with a thickened end wall 10, the latter having a central opening therethrough, as at 11, to receive the unthreaded end of the shaft and having its outer end reduced in diameter to more nearly approximate the diameter of the washer 5. The nut 7 is cylindrical and of an external diameter equal to the internal diameter of the bushing seat; while the threaded bore is adapted to receive the threaded portion of the shaft. The remaining part of the tool used in extracting a bushing is in the form of a wrench 8, consisting of a flat metal plate with spaced apart spanner jaws 12 and 13 at the lower end and a pair of spanner jaws 14 and 15 at the upper end, the jaw 15 being in the form of a bell-crank lever with the upper portion thereof constituting the jaw bent to one side so as to align with the companion jaw 14, while at the lower end of said bell-crank lever there is pivoted a dog 19 in line with the plate forming the wrench so as to engage an adjoining edge of said plate. By reference to Fig. 3 it will be noted that the bell-crank lever is pivoted to one side of the plate forming the body portion of the wrench and that the dog is pivoted at the inner side of the bell-crank lever for the alignment and engagement thereof as hereinbefore stated.

Now in extracting a bearing the sleeve 6 is mounted on the shaft 1 so that the thickened end wall thereof will bear against the washer 5 and its open end extend towards the threaded end of said shaft, the shaft being then inserted axially through the bearing or bushing 20, located in the wrist-pin bearing 21 of piston 22 and screwed into the nut 7 which

for the purpose is held in the piston between the two wrist-pin bearings; after which the jaws 14 and 15 of the spanner-wrench are placed in engagement with the 5 nut to prevent rotation of the latter when the shaft is turned to extract the bushing, the engagement of the wrench being effected by swinging movable jaw 15 outward, after disengaging pawl 19, and after the inwardly 10 projecting ends of the jaws 14 and 15 are inserted in recesses 23 and 24 in opposite side edges of the nut said pawl or dog drops into position to engage the edge of the body portion of the wrench for holding the wrench in 15 connection with the nut. By reference to Fig. 1 it will be noted that when the parts of the tool are in this position with respect to the cylinder and bushing to be removed the turning of shaft 1 by handle 2, and holding 20 the wrench stationary will result in pressing the nut against the bushing and thereby forcing it into the sleeve 6, which latter during this operation presses against the outer side of the piston. In practice a nut of a length 25 approximating the distance between the two wrist-pin bearings 21 and 22 may be and preferably is employed to permit the bushing to be entirely removed into the sleeve, the said nut being engaged by the wrench at its inner 30 end or distant from the bushing being removed. Furthermore, by having the shaft of the same diameter as the internal diameter of the bushings and of a length greater than the diameter of the piston said shaft may extend through both bushings so that it will be held in perfect alignment to properly guide the bushing being removed and thereby prevent it from binding or jamming in the bearing, enabling the operator to easily and conveniently remove both bushings from a piston, it being understood that the shaft is so aligned in both instances—in one instance by the old bushing opposite the one being removed and the new one inserted, and in the 40 other instance by the new bushing on reversing the tool and passing it through the remaining old bushing into the new one.

For the purpose of inserting a bushing into the wrist-pin bearing of the piston, as illustrated in Fig. 2, I employ in connection with the shaft and spanner-wrench another form of nut, designated by the numeral 25 (Fig. 2), said nut being provided with an annular recess 26 at one end to receive the inner end of the inserted bushing so that it may project beyond the inner end of the wrist-pin bearing, the rim 27 around the aforesaid recess being adapted to engage the inner end of the bearing, 21 or 22, while the other end of said nut is provided with recesses 28 and 29 in its opposite edges for engagement of the spanner-wrench to hold this nut against rotation in the same manner and for like purpose as nut 7 is held, but in this instance nut 25 being of greater diameter

than nut 7 so as to engage the wrist-pin bearing instead of passing into the same it is embraced and engaged by the wider spaced jaws 12 and 13, and the said nut 25 being narrower than the space between the wrist-pin bearings the jaws 12 and 13 are integral with the body of the wrench and engage the aforesaid recesses 28 and 29 by moving the wrench laterally. In the operation of inserting a bushing the latter is pushed on to the shaft from the threaded end thereof and positioned on the unthreaded portion of said shaft against the washer 5. The shaft is then inserted through the bearing into and through nut 25 on and through the opposite bushing, after which the nut is brought up against the inner end 30 of the bearing and held by the wrench so that when the shaft is turned the bushing will be forced into place, bearing at its outer end against washer 5, for in this instance sleeve 6 is dispensed with, and as the shaft is centered by the opposite bushing alignment will be maintained for the proper insertion of the new bushing.

In both instances, removing a bushing and inserting a new one, the length of the shaft or screw by which the required power is applied provides for accurately centering said shaft to effectively prevent the bushing from becoming jammed in the wrist-pin bearing; consequently the ends of the wrist-pin bearings could be untrue or warped without affecting the operation of the tool which is aligned by the bushings as hereinbefore stated. For instance, if the inner end 30 of the wrist-pin bearing was warped, or not true, the nut 25 pressing against the same would have a tendency to be thrown out of alignment and the shaft likewise disturbed thus affecting the alignment of the bushing with respect to the bearing in which it is being inserted, but in the present instance this is avoided by having the operating shaft or screw extend through the opposite bushing for accurately centering said screw and the bushing thereon either in inserting a bushing or removing an old bushing.

From the foregoing description in connection with the accompanying drawings it will be readily seen that I provide a tool for removing and inserting bushings in the wrist-pin bearings of an engine piston that will afford the required power to accomplish the operations easily and effectively, and although I have herein disclosed the preferred embodiment of my invention it will be understood that modifications or changes may be made within the spirit and scope of my claims.

I claim:

1. A tool for operating on spaced aligned bushings comprising a screw threaded shaft of a diameter throughout its length equal to the internal diameter of the bushing to be operated upon and of a length greater than

the distance between the outer ends of said aligned bushings, a compression member, and a nut threaded on the shaft intermediate the bushings to cooperate with said compression member.

2. A tool for extracting bushings comprising a screw threaded shaft of a diameter throughout its length equal to the internal diameter of the bushing to be extracted, a thrust portion and operating means at the end of said shaft, a cylindrical element closed at one end and loosely mounted on said shaft, coaxial therewith, having an internal diameter equal to the external diameter of the bushing to be operated upon, the closed end of said element having an opening to receive said shaft and bear against said thrust portion, and a nut of a diameter about equal to the external diameter of said bushing operatively engaging said shaft intermediate the bushings and adapted to receive a wrench.

3. A tool for operating upon bushings in spaced alignment comprising a shaft threaded for the major portion of its length with a plain portion at the inner end thereof, said shaft being of a diameter throughout its length equal to the internal diameter of the bushings to be operated upon and of a length greater than the distance between the outer ends of said aligned bushings, a cup-shaped compression member the internal diameter of which is equal to the external diameter of the bushings and the closed end of said compression member having a plain opening to receive the plain portion of the shaft intermediate the bushings, and a nut threaded on the shaft to cooperate with the compression member.

4. A tool for extracting bushings comprising, a threaded shaft having a thrust portion and operating means at one end thereof, said shaft being of a diameter equal to the internal diameter of the bushing to be extracted, a cylindrical element loose on said shaft, coaxial therewith, having an internal diameter equal to the external diameter of the bushing to be extracted, said element having a closed end with an opening to receive said shaft and bear against said thrust portion, and a nut operatively engaging the shaft, said nut having recesses at opposite sides of one end thereof adapted to receive a wrench having spanner jaws for engaging said recesses.

5. A tool as described in claim 4 said wrench comprising a flat piece of metal, having one stationary jaw and one movable jaw.

JOHN D. HAMAN.
